DEMOUNTABLE CAMPER

Robert D. Matz, 316 N. Walnut, Mishawaka, Ind. 46544

Filed Sept. 27, 1965, Ser. No. 87,164

Term of patent 3½ years

(Cl. D14—3)

FIG. 1

FIG. 2

FIG. 3

The side opposite to that shown in FIGURES 1 and 2 embodies the same design features, and hence has not been shown herein.

I claim:

The ornamental design for a demountable camper, substantially as shown and described.
